CLOCK CASING

David W. Miley, Peru, and Ellsworth R. Danz, La Salle,
Ill., assignors to General Time Corporation, Stamford,
Conn., a corporation of Delaware

Filed Feb. 14, 1968, Ser. No. 10,574

Term of patent 14 years

(Cl. D42—7)

FIG. I

Des. 212,030

PAGE 2

FIG.2

FIG.3

FIG.4

FIG. 1 is a front elevational view of a clock casing showing our new design, the hands and indicia shown in broken lines being for illustrative purposes only;

FIG. 2 is a rear elevational view;

FIG. 3 is a top plan view; and

FIG. 4 is a side elevational view.

We claim:

The ornamental design for a clock casing, substantially as shown and described.
